UNITED STATES PATENT OFFICE.

LEE P. HYNES, OF ALBANY, NEW YORK, ASSIGNOR TO HYNES & COX ELECTRIC CORPORATION, OF ALBANY, NEW YORK, A CORPORATION OF NEW YORK.

IMMERSION HEATER.

Application filed December 6, 1924. Serial No. 754,332.

For a detailed description of the present form of my invention, reference may be had to the following specification and to the accompanying drawings forming a part thereof, 5 wherein

Fig. 1 shows my completed device,
Fig. 2 the sheath-plug,
Fig. 3 the detachable heater element,
Fig. 4 the junction box,
10 Fig. 5 the container, and
Fig. 6 a cross-section of heater and sheath.

My invention relates to an immersion heater for use in the electric heating of fluids in tanks, boilers or other containers. In particular my device is so organized as to avoid the necessity of draining the tank or boiler when replacement of a burned out coil, or change to a coil of different power, is desired. My device is also of a simple, cheap and rugged character.

Referring to Fig. 2, the part D is a length of flattened copper tube which is closed and sealed at its right end and at its left end is welded into the floor E of a screw-plug, its 25 flat bore coming flush with the said floor E. Beside the floor E the said plug contains the hollow threaded portion G and the chambered hexagonal head B. To one flat face of head B is fastened an angle-plate P which is to form 30 the bottom of a junction box or chamber and is provided, if desired, with an opening F within which a conduit tube may be fastened. In Fig. 3, which illustrates the heating element, H is a plate of thin sheet metal having 35 its side edges turned over to overlap the side edges of a similar plate J. Between the said plates there is a flat heating coil suitably embedded in refractory insulation. Such a coil is a familiar device that does not require illustration. L and M are the insulated terminals 40 of the coil which are located on the side of the plate J at the outer end thereof. The plate H is turned up at its outer end to form a lip K which, when the heating element is 45 thrust into the sheath-plug of Fig. 2, will abut against the down-turned lip A of plate P. Then a U-shaped plate C, Fig. 4, is placed around the plate P, its two ends abutting the face of the head B. Finally a screw-bolt is 50 passed through the overlapping lips K and A and through the flat end of plate C. This single bolt secures all of the parts firmly together, producing the completed article as shown in Fig. 1. This instrument may be 55 readily inserted in a tank, boiler or other ves-

sel and the part G screwed into an ordinary pipe-tapping on the vessel. For example, in Fig. 5 I have shown at S a tubular container having top and bottom connections with a second container W for circulation of fluid through both containers. The container S is open at its bottom for the insertion of a sheath-plug such as I have described, the pocket portion D extending upward inside the container, with the plug portion B screwed into the container wall and the junction box P beneath it. Thus the said pocket opens outside of the container and the electric heater may be readily inserted therein as above described with its terminals enclosed 70 by the junction box. This involves no draining of either container nor the need of valves to shut off container S from the large container W. When thus in place the heating element can be readily removed, leaving the 75 sheath-plug still in place and constituting a sealed pocket immersed in the fluid in the vessel into which pocket another, or the same, heating element may be thrust and secured, as above described. The instrument is strong 80 and rugged, simply made and manipulated and is cheap to manufacture.

It is also desirable in certain cases to give the instrument a higher rating in watts per heater than is permitted by the degree of thermal connection between the heating element and the sheath that is attainable in the precise arrangement above described. In such cases I may introduce a filling material of suitable thermal conductivity between the heating element and the surrounding sheath. Preferably I fill the sheath with such material in a liquid or semi-plastic condition. Then I insert the heater, which, as it is pushed in displaces and squeezes out the excess material 85 leaving the heating element in the sheath surrounded with a very thin film of the said material. This material also fills up the space on plate J between the overlapping edges of plate H, as appears in the cross sectional view 100 in Fig. 6 taken through the pocket D of the sheath-plug and the heater encased thereby.

What I claim as new and desire to secure by Letters Patent is:

1. An immersion heater comprising a 105 sheath member, a heater element complementary to and removably positioned within said sheath member so as to have one end project therefrom, and means carried by said sheath member and positioned to engage the pro- 110

jecting portion of the heater element for normally preventing withdrawal thereof from said sheath.

2. An immersion heater comprising a sheath member, a heater element complementary to and removably positioned within said sheath member, and an angle plate carried by said sheath member and positioned to normally prevent withdrawal of said heater element.

3. An immersion heater comprising a sheath member, a heater element complementary to and removably positioned within said sheath member, said heater element having an offset lip, and means carried by the sheath member and cooperating with said lip to normally prevent withdrawal of said heater element.

4. An immersion heater comprising a sheath member, a heater element complementary to and removably positioned within said sheath member, said heater element having an offset lip, and an angle plate carried by said sheath member and cooperating with said lip to normally prevent withdrawal of said heater element.

5. An immersion heater comprising a sheath closed at one end and open at the other, an attaching plug having an opening within which the open end of said sheath is secured, a heater element complementary to said sheath and removably positioned therein so as to have one end projecting therefrom, and means carried by said plug and positioned to engage the projecting portion of said heater element for normally preventing withdrawal thereof from said sheath.

6. An immersion heater comprising a sheath closed at one end and open at the other, an attaching plug having an opening within which the open end of said sheath is secured, a heater element complementary to said sheath and positioned therein, and an angle plate exteriorly attached to said plug and positioned to normally prevent withdrawal of said heater element.

7. An immersion heater comprising a sheath closed at one end and open at the other, an attaching plug having an opening within which the open end of said sheath is secured, a heater element complementary to said sheath and removably positioned therein, said heater element having an offset lip, and means carried by said plug and cooperating with said lip to normally prevent withdrawal of said heater element.

8. The combination with a sheath member of a heater element removable therefrom at will, said heater element consisting of two superposed plates having a heater coil interposed between them, one of said plates having its side edges overlapping the contiguous edges of the other plate, and means carried

by said sheath and cooperating with the last mentioned plate to normally prevent withdrawal of the heater element from said sheath.

9. The combination with a sheath member of a heater element removably positioned therein, said heater element consisting of two superposed plates having a heater coil interposed between them, one of said plates having its side edges overlapping the contiguous edges of the other plate, the last mentioned plate having a lip at one end, and means carried by said sheath and cooperating with said lip to normally prevent withdrawal of said heater element.

10. The combination with a sheath member, of a heater element removably positioned therein, said heater element consisting of two superposed plates normally held against separation and having a heating coil interposed between them, one of said plates having an offset lip at one end, and means carried by said sheath and cooperating with said lip to normally prevent withdrawal of said heater element from said sheath.

11. The combination with a sheath member, of a heater element positioned therein and removable therefrom at will, said heater element consisting of two superposed plates having a heating coil interposed between them, the edges of one of said plates overlapping the contiguous edges of the other plate, and a filling of thermal conducting material interposed between the heater element and the sheath member.

12. The combination with a sheath member, of a heater element positioned therein and removable therefrom at will, a filling of thermal conducting material interposed between the heater element and the sheath, and means normally preventing withdrawal of said heater element.

13. An immersion heater comprising a sheath member, a heater element positioned therein and removable therefrom at will, said sheath member and said heater member having complementary means for normally preventing withdrawal of said heater element, and means cooperating with said withdrawal-preventing means for forming a junction box.

14. An immersion heater comprising a sheath member, a heater element removably positioned therein and provided with a lip, an angle plate carried by said sheath member and cooperating with said lip to normally prevent withdrawal of said heater element, and side plates cooperating with said lip and said angle plate to form a junction box.

Signed at Albany, county of Albany and State of New York, this 22nd day of November, 1924.

LEE P. HYNES.
